[57] CLAIM

The ornamental design for a miniature coffin cigarette case, substantially as shown.

DESCRIPTION

FIG. 1 is a front elevational view of my miniature coffin cigarette case showing my design.

FIG. 2 is a top plan view thereof.

FIG. 3 is a rear elevational view thereof.

FIG. 4 is a bottom plan view thereof.

FIG. 5 is an elevational view of the left-hand side thereof.

FIG. 6 is an elevational view of the right-hand side thereof.

FIG. 7 is an isometric view thereof showing the lid of my miniature coffin cigarette case in a raised position.
